TROLLEY HEADS

Stanley Livingstone White, Sunnyside, Pretoria,
Union of South Africa

Application August 13, 1952, Serial No. 304,090

1 Claim. (Cl. 191—59.1)

This invention relates to trolley heads or current collectors as provided at the extremities of the booms of electric trolley buses, trackless trams and the like for contacting overhead current supply wires. It relates more particularly to that common construction of such heads wherein a trough-section shoe by which the wire is contacted and which is swivelable in relation to a body connecting it to the boom is liable, on disengagement from the wire and especially where it assumes a transverse or oblique relationship thereto, forcibly to engage and even become hooked to span wires supporting the supply wires, and overhead fittings or supports of various kinds particularly those running transversely of the supply wires or the plane of the boom or presenting surfaces so disposed: with the result of tearing the head from the boom and/or seriously damaging such span wires or other devices.

According to the invention in a trolley head of the type above referred to, there is interposed between the pivotal connection of the shoe and that part of the body which is connected to the boom, a spring-loaded hinged connection enabling the shoe temporarily to recede rearwardly and downwardly in relation to the remainder of the head, on impact with such devices as aforesaid and to pass thereunder without any of the foregoing disadvantages.

More particularly the body is formed in two transversely hinged sections, the lower or forward one of which is connected to the boom whilst the rear section carries the usual upright pivot about which the shoe supporting saddle is free to rotate (to accommodate lateral obliquity of the boom in relation to the wire) and to which it is connected on a transverse pivot (to accommodate height variations of the wire from the ground). The hinge is spring-loaded in such a way as ordinarily to compact the body sections and maintain the shoe in normal raised operative position for engaging the shoe trough with the wire.

Any sharp load or impact received on the shoe, as when it leaves the wire and assumes a crosswise position in relation to the same, will merely result in resilient rearward and downward deflection of the whole rear section aforesaid, allowing the obstruction whatever be its nature, to slide easily over the head, the two sections of the body thereafter reassuming their original and normal compacted and operative position.

To obviate possible catching of the cross wires or other such obstruction in the opening between the two sections of the head body when the shoe carrying section is thus deflected, a guard member is provided which is fixed to the latter section so as to partake of its aforesaid deflecting movement and present at all times a barrier over the said opening also assisting the obstruction to slide easily over the shoe.

Conveniently the spring loading of the two sections into their normal compacted position is obtained by a compression spring of suitable strength, operative between abutments attached respectively to or otherwise provided by the said sections below the head as a whole; and a shunt or conductor relieving the aforesaid pivotal

2

connection between the body sections from the duty of carrying the current between these sections is conveniently a flexible wire or like strip spanning the said spring abutments.

5 Downwardly projecting parts such as the spring and abutments aforesaid are conveniently underlaid by a guard member extending rearwardly from the forward section of the body and designed to prevent such parts from catching over supply wires or other such overhead fittings, 10 e. g. during attempts at replacing the shoe against the supply wire.

The invention may be applied as a modification to existing heads in the following simple manner. The body is parted transversely at a short distance in front 15 of the shoe-supporting saddle pivot pin and the two sections are reconnected by a transverse pivot pin through the lower rear part of the forward or boom-socket section. The rear section may have wing lugs welded to it to receive the ends of the transverse pivot pin and a down-

wardly directed lug providing a connection and abutment for the rear end of a compression spring extending forwardly below the rear end of the forward body section. This last may have an angle piece welded underneath it providing a second downwardly extending lug in front 20 of and in line with the first downwardly extending lug to constitute a connection and abutment for the forward end of the said spring which thus acts outwardly resiliently to hold the body sections in their normal operative relative positions. The flexible shunt is conveniently 25 pinched at its end between the lugs and the spring ends with the aid of suitable screws through the lugs.

A run of stout steel or like wire or rod welded to the front body section just behind the boom socket may pass obliquely down to the rear to be welded to the second 30 mentioned lug, thence passing below the spring and curving upwardly towards the base of the shoe saddle pivot pin; thus to provide the second mentioned guard.

The guard for the opening between the body sections and above their transverse pivotal connection may be an 35 upwardly curved tongue-like extension from the front of the rear body section near the plane of parting of the two sections, the extension curling upwardly into and rearwardly out of the usual hollow box formation of the upper part of the body in front of the shoe and ending 40 close to the upper perimeter of the saddle, the movements of which the extension follows about the transverse pivot whereby at all times to span the gap between the saddle and the front section of the body.

In an alternative construction of base guard the same 45 may consist of a short run of rod from the socket to the nearer or forward lug, and a second run from the other or rear lug upwardly curving behind the base of the rear section of the head, the coils of the spring itself being sufficiently closely wound to provide a smooth junction 50 between the two guard runs to obviate catching of cross-wires. In either case the guard may provide a loop for the hook of the usual stick or pole for replacing a dewedired head.

To enable the present invention to be more clearly 55 understood and carried into practice, reference is now made to the accompanying drawings in which like reference numerals refer to like parts throughout the several views.

In the drawings:

60 Figure 1 is a side elevation of a trolley head constructed according to the invention;

Figure 2 is a side elevation of a slightly modified construction of the invention; and

Figure 3 is an end view of Figure 2 looking in the direction of the arrow "A" after removal of the rear body part carrying the shoe.

70 Referring to Figure 1 of the drawings reference 1

denotes the top end of the usual current collector boom to which the body part 2 of the head is attached by being made in the form of a socket secured to the boom by a clamping bolt passing through the hole 3. This body part 2 is provided with the usual hollow deflector 4.

The pivotal body part 5 is connected to the socket body part 2 by the pivot bolt 6 which passes through two holed lugs 7 and a coacting holed portion of the part 2. This body part 5 carries the usual pivoted saddle top 8 with its conductor receiving shoe 9.

The body part 2 is normally held in its operative position as shown by a compression spring 10 interposed between an angle abutment 11 on the body part 2 and a similar abutment 12 on the body part 5. A flexible current conductor cable 13 forms permanent electrical connection between the two body parts. A guard member 14 underlies the two abutments 11 and 12 and the bottom end of the swivel pin 15 of the saddle top 8.

To prevent cross wires or the like from slipping into the opening between the two sections of the head when the body part 5 is deflected, a guard member 16 in the form of a bent metal strip is fixed as by welding to the top of the body part 5, while its free end is arranged to project under the top portion of the deflector 4.

Figures 2 and 3 show a slightly modified construction of trolley head. In this case the pivotable body part 5a is connected to the socket body part 2a by a pivot pin 6a passing through a lug 17 on the part 5a and two spaced lugs 18 on the end of the socket part 2a.

The lower end of the part 5a is provided with two lugs 19 by means of which this part is pivotally connected to a rod 20 provided with a spring abutment flange 21 which is fixed to a guide cylinder 22 slidably coacting with a complementary guide cylinder 23 fixed to a spring abutment disc 24 which is anchored against the rounded stop abutment 25 provided on the end wall of a guard casing 26.

A compression spring 27 located between the parts 21 and 24 normally holds the body part 5a in its operative position as shown in Figure 2. Two flexible cables 28 form permanent electrical connection between the body parts 2a and 5a. The loop 29 is provided to receive the hook of the usual stick or pole for replacing a dewired head.

What I claim is:

In a trolley head comprising a body having one portion socketed for fixing to a boom and another portion located generally rearwardly of the socketed portion, a member carrying a conductor wire-contacting shoe, substantially upright swivel connection between the shoe-carrying member and said other body portion, a horizontally arranged pivotal connection between the two body portions located generally below the shoe-carrying member, and spring means located below the socketed body portion compressively reacting on the other body portion to resist rearward and downward tilting movement thereof about the horizontally arranged connection, an upwardly and rearwardly inclined formation over the socketed body portion serving upwardly to deflect an encountered obstruction in relation to the shoe, and a guard member attached to and movable with the other body portion which member extends into and coacts with the said formation to prevent such obstruction from entering between said formation and the shoe-carrying member.
